UNITED STATES PATENT OFFICE

EDWIN L. CONNELL, OF CLEVELAND, OHIO, ASSIGNOR TO THE VAN DORN ELECTRIC
TOOL CO., OF CLEVELAND, OHIO, A CORPORATION OF OHIO

DRILLING OR TAPPING MACHINE

Application filed May 23, 1929. Serial No. 365,358.

This invention relates to motor driven machines, its object being to provide a simple and improved arrangement of control mechanism adaptable for use on either drilling, tapping, stud setting or like machines, and so devised as to terminate the drilling, tapping or stud setting operation by the torque resistance and restore the motor to operative condition by the usual operation of retracting the tool from the work, whereby the machine is more or less automatic in operation, but nevertheless is controlled by the operator with his usual manipulations of such machines.

15 Further objects of the invention are in part obvious and in part will appear more in detail hereinafter.

In the drawings, Fig. 1 represents a front elevation of a portion of a drilling machine embodying the invention; Fig. 2 is a detail elevation illustrating the switch mechanism, the cover of the switch casing being omitted for the clearness of illustration; Fig. 3 is a sectional plan view through the cover of the switch, the section being taken on approximately the line 3—3, Fig. 1; Fig. 4 is a detail section on the line 4—4, Fig. 2; Fig. 5 is a sectional elevation of a tapping or stud setting machine embodying the invention; Fig. 6 is a sectional elevation through the controlling portion of the operating handle; and Fig. 7 is a wiring diagram of the control system.

The drilling machine shown in Fig. 1 comprises an arm or support 1 mounted to swing about and also adjustable vertically upon a post or column, not shown. This radial arm carries a head or frame 2 including a post 3 provided with a head 4 carrying a bearing sleeve 5 in which is vertically slidable a rod or shaft 6 attached to a sub-frame 7 in which is mounted, preferably detachably, a portable tool, such as a portable electric drill indicated generally at 8 and including an electric motor, its casing, any necessary speed reducing gearing, and a tool spindle 9. The sub-frame 7 usually is provided with an arm having a eye 10 guided by and travelling along the post 3. A compression spring 11 adjustable by the nut 12 serves to normally elevate the sub-

frame 7 and the tool carried thereby to the upper most position. The tool is brought into engagement with the work by the operator, who depresses a handle or lever 13 pivoted at 14 upon the sub-frame and having a short arm connected by a link 15 to the head 4.

The electrical control system for this tool is shown in Fig. 7, where the three wire A. C. circuit leads 16a, 16b and 16c are connected to the main switch, indicated generally at 17, and including contacts 18 in all of said leads actuated by a relay coil 19 adapted upon energization of said coil to close the main switch and complete the circuits to the motor M. The main switch also carries an extra set of controlling contacts, marked 20, which are in a circuit 21 from one of the leads, such as 16a, with a normally closed overload switch 22, a normally closed gauge stop switch 23, (if use of such a stop is desirable) a normally closed emergency stop switch 24, and coil 19 to another lead 16b. The control circuits also include a starting circuit 25 in circuit with the normally open start switch 26.

In the arrangement shown in Fig. 1 a gauge stop is not used but it may be employed, as will appear.

In the use of this apparatus the motor is started by closing the starting switch 26, which energizes coil 19 through the normally closed stop button 24 and closes the motor circuits at the main switch. Control contacts 20 are also closed, thereby establishing a maintaining circuit by way of contacts 20, switches 22, 23 and 24 through the coil 19 and permitting the start switch to be released and move to open position. The motor will continue to run. The operator pulls down the lever 13 and then applies the tool to the work. The tool may be a drill, a tap, a stud or nut setter, or the like. Assuming that a bolt is to be screwed home in an engine block, when the bolt reaches its home position considerable torque resistance is immediately encountered, causing a rush or rise of current flow through an overload coil 27 in one of the motor leads, thereby actuating a movable core to open the switch 22 and break the circuit to the coil 19, thereby opening the motor circuits and contacts 20. The overload switch 22 is normally

closed, or in other words, is of any suitable self-closing form, in the sense that it is only open when the overload coil 27 is energized, and at any time when said coil is deenergized 5 the switch 22 promptly moves of itself to closed position.

In this mechanism the starting switch is of the form shown in Fig. 2. It includes a casting 28 mounted on one side of the head 4 10 and in which is located an arcuate insulating block 29 carrying two oppositely disposed similar conducting segments 30, 30a. Cooperating with said segments is a yielding conducting roller 31 carried by an arm or lever 32 pivoted at 33 and connected by a link 34 to the moving sub-frame 7, so that motion of the sub-frame swings the lever 32. On the cover 28a of the switch casing is the 15 normally closed yielding stop button switch 24, shown in Fig. 3. Circuit wires from this switch lead one to the conducting segment 30 and the other to the main relay coil 19. Segment 31 is also connected by a wire 35, 36 to the overload switch 22. Segment 30a is on 20 the opposite side of block 29 and insulated from segment 30. As the roller 31 travels along its arcuate path it simultaneously engages the segments 30 and 30a and conductively bridges them, thereby completing the 25 starting circuit.

Fig. 2 shows the switch parts in the position corresponding to Fig. 1, with the tool in its uppermost position. The starting switch 26 is therefore energized by the travel of the 30 tool toward its upper position, or will be energized upon the first depression of the tool by the handle 13, which causes roller 31 to contact simultaneously with the segments 30 and 30a, and thereby complete the circuit 21, 35 25, 26, 24, 19, Fig. 7, and energizes coil 19, thus closing contacts 20 and maintaining said contacts and the motor circuit closed even when the tool is further depressed and roller 31 reaches the insulated part 29 of the segment. 40 As before stated, the tool is engaged with the work and performs its duty until the over-load coil 27 opens switch 22, whereupon the motor circuit is opened, the motor stops, switch 22 promptly closes, and the operator 45 disengages the tool from the work and moves or permits it to move to its uppermost position, thereupon instantaneously completing the starting circuit by closing of the starting switch, as before. The tool is therefore operating 50 and ready for another cycle of duty as before, but the operator need give no attention to the control mechanism except to press the emergency or stop button 24 when he wants to stop the tool at other times than 55 by the operation aforesaid.

Figs. 5 and 6 show another embodiment of the invention particularly adapted for screwing or threading operations, such as tapping, including a tool head 40 on which is mounted 60 a driving motor 41 connected by the gear-

ing generally represented at 42 to drive a shaft 43 provided with two pinions 44, 45, the former engaging a pinion 46 splined on a longitudinally slideable sleeve member 47, and the latter engaging an intermediate pinion 48 reversely driving a pinion 49 splined on a longitudinally slideable sleeve 50, sleeves 47 and 50 being interconnected by the ball bearing 51 but rotating in opposite directions. The upper sleeve 47 carries a forwardly driving clutch member 52 and the lower sleeve a reversely driving clutch member 53, the two clutch members cooperating with a clutch member 54 upon the tool spindle 55, which slides and rotates in both sleeves, its movement being limited by collars 55a, 55b at its upper and lower ends. The lower sleeve 50 is provided with a grooved collar 56 engaged by rollers in lever or arm 57 connected by a link 58 to a stationary point on the main frame. The lever also carries a gauge stop 59 adjustable as to length and having a gauge portion 60 designed to engage the work when a desired depth or home position is reached, and also including a shank 61 travelling in a guide 62 and normally held downwardly by a spring 63. At the upper end of said rod 59 is the switch 23, including a bridge contact 65 cooperating with stationary contacts and forming the normally closed but openable switch conventionally indicated in Fig. 7.

The starting switch in this arrangement is of the form shown in Fig. 6. The lever 57 is of elbow form having a handle portion 65 pivoted at 66 and carrying two fingers 67, 68 which limit its swinging movement on the lever. One of said fingers carries a member 69 adapted to engage and depress a push button 70 for actuating a yieldable normally open switch 26, the details of which are immaterial except that the pressure of the spring 27a which normally opens the switch may be fairly strong for reasons which will appear.

In this arrangement the tool spindle 55 and the coupled sleeves 47, 50 move downwardly by gravity. The control system is of the same form shown in Fig. 7, the main switch and overload coil being conveniently mounted on any suitable support, such as a part of the frame 40.

Assuming the machine at rest, the lever 57 is raised by raising the handle 65, which disengages the upper clutches and engages the lower reverse clutches, further upward movement of the handle 65 against the weight of the sleeves and tool spindle being sufficient to overcome the pressure of spring 27a and close the yielding switch 26, which starts the motor and establishes the maintaining circuit through contacts 20 and coil 19 before referred to. The handle is then lowered and the sleeves and tool spindle being sufficient to the tool is applied to the work, its advance being stopped while the sleeves 47, 50 move

downwardly until the tool rotates forwardly, whereupon the tool is screwed into the work until gauge 60 opens switch 23 or until the torque rise causes current rise in the coil 27 sufficient to open the switch 22, whereupon the motor circuits are broken and the motor stops. This takes the load off from the forward clutches and the operator raises the handles 65, and sleeves 47, 50, thereby first opening the forward clutch and closing the reverse clutch, whereupon further elevating movement of the handle 65 closes the starting switch and re-energizes the motor so that the tool spindle is driven in the reverse direction and the tool is retracted from the work. This leaves the machine with the motor running ready for another operation, even through the operator has performed no more than his customary manipulations.

What I claim is:

1. Apparatus of the class described, comprising a tool spindle mounted for rotating and reciprocating motion, an electric motor and circuit for rotating said spindle, a control circuit, a relay therein for controlling both the motor circuit and the control circuit, normally closed switch means in the control circuit for controlling the motor circuit, means sensitive to the current supplied to the motor through the motor circuit for actuating said switch means to open the control circuit, thereby causing said relay to open the motor circuit, an operator operated device for advancing and retracting the tool spindle, and switch means actuated by spindle retracting operation of said device for affecting said relay to complete the motor circuit.
2. Apparatus of the class described, comprising a tool spindle mounted for rotating and reciprocating motion, an electric motor and circuit for rotating said spindle, a control circuit, a relay therein for controlling both the motor circuit and the control circuit, normally closed switch means in the control circuit for controlling the motor circuit, means sensitive to the current supplied to the motor through the motor circuit for actuating said switch means to open the control circuit, thereby causing said relay to open the motor circuit, an operator-operated device for producing reciprocating motion of said tool spindle, and switch means actuated by reciprocating motion of said tool spindle for affecting said relay to complete the motor circuit.

In testimony whereof I hereby affix my signature.

60

EDWIN L. CONNELL.

CERTIFICATE OF CORRECTION.

Patent No. 1,852,736.

Granted April 5, 1932, to

EDWIN L. CONNELL.

It is hereby certified that error appears in the printed specification of the above numbered patent requiring correction as follows: Page 2, line 128, strike out the words "the sleeves and tool spindle being sufficient to"; and that the said Letters Patent should be read with this correction therein that the same may conform to the record of the case in the Patent Office.

Signed and sealed this 17th day of May, A. D. 1932.
